UNITED STATES PATENT OFFICE

2,361,182

CATALYTIC CONVERSION OF OIL

Du Bois Eastman and Charles Richker, Port Arthur, Tex., assignors to The Texas Company, New York, N. Y., a corporation of Delaware

Application December 24, 1941, Serial No. 424,248

4 Claims. (Cl. 196—52)

This invention relates to the catalytic conversion of hydrocarbon oil to gasoline hydrocarbons suitable for motor fuel.

The invention has to do with a process for catalytic conversion of oil by contact with a mass of active catalyst in solid fragmentary form confined within a reaction zone, involving alternate periods of oil conversion and catalyst regeneration in situ, carbon being deposited upon the catalyst during the conversion periods, and being removed therefrom during the regeneration periods by combustion during flow of an oxygen-containing gas through the reaction zone.

The invention broadly contemplates correlating the conditions of operation during the conversion periods so as to remain onstream during the conversion periods for a substantial period of time, obtaining a relatively high rate of conversion to gasoline hydrocarbons and forming a carbonaceous deposit upon the catalyst such that during catalyst regeneration, reactivation can be confined to a relatively thin section of combustion which propagates, in a comparatively gradual manner, from one end to the other end of the contact mass in the direction of flow of regenerating gas therethrough.

More specifically, the invention has to do with the catalytic cracking of a relatively clean gas oil stock to form gasoline hydrocarbons wherein the onstream period of conversion is prolonged to substantially more than 1 hour, as, for example, a period of about 3 to 4 hours and even higher, obtaining a relatively high yield of gasoline at least in the range about 25 to 35% by weight of the feed oil, and depositing upon the catalyst at least 3% and preferably about 5 to 15% of carbon by weight of the catalyst.

In catalytic cracking, a stream of oil in substantially vaporized form and heated to a conversion temperature in the range about 800 to 1100° F. is passed through a catalyst bed maintained at the conversion temperature so as to convert the oil to gasoline hydrocarbons. The conversion to gasoline hydrocarbons is accompanied with concomitant breakdown of a portion of the feed oil to gas and coke or carbonaceous material, which latter is deposited upon the catalyst. As a result of this carbonaceous deposit the activity of the catalyst, as measured by the percentage conversion to gasoline and gas, decreases. It has been customary to operate such a process with an exceedingly short conversion cycle or onstream time and thereafter terminate the flow of feed hydrocarbon through the catalyst bed, following which the bed is reactivated by passing

therethrough a highly heated gas containing air or oxygen to burn off the carbon deposit and thereby restore the activity of the catalyst.

In the regeneration of the catalyst by burning it is important to avoid exposing the catalyst to temperatures sufficiently high to destroy its activity. Thus, with an alumina-silica gel type of catalyst it is usually desirable to avoid exposing it to temperatures much above about 1250° F. Combustion of carbon being of a highly exothermic nature, large amounts of heat are liberated and, therefore provision must be made for removing the liberated heat so as to control the temperature prevailing within the contact mass during regeneration.

It has been observed that the combustion of a carbonaceous deposit from a contact mass may involve any one of three general types, namely, a flash burn, a diffused burn, and a narrow flame front burn, depending upon conditions prevailing during the regeneration and the extent of the carbonaceous deposit. In the flash burn a superficial layer of carbon is burned off rapidly, while the remaining carbon contained within the pores of the catalyst is either not removed or else incompletely removed with considerable difficulty. Such type of burn usually occurs where the rate of flow of regenerating gas is quite high, i. e., about 10,000 volumes of gas (measured at atmospheric pressure and temperature) per volume of catalyst.

The diffused type of burn is one in which all of the carbon throughout the entire mass of the catalyst is burned substantially simultaneously. In such case the catalyst is usually exposed to excessively high temperatures unless special provision is made for removing the heat of combustion substantially as rapidly as it is liberated. Moreover, the exit gases contain substantial amounts of free oxygen. This type of burn is associated with a small amount of carbon deposit per unit of catalyst.

With the narrow flame front type of burn actual combustion of the carbon is confined to a relatively thin section which may range from about one-half to several inches in thickness and this thin section of flame propagates relatively slowly through the contact mass in the direction of flow of the reactivating gas. Thus, the hot zone within the contact mass is at all times confined to a relatively small area. As a consequence, the liberated heat of combustion can be readily removed from the contact mass as sensible heat of the reactivating gas, particularly

where the oxygen content of the reactivating gas is restricted to about 2 or 3% of the reactivating gases and the reactivating gas is caused to flow through the contact mass in relatively large volume. The introduction of oxygen is controlled so that there is complete consumption of oxygen as the flame front advances through the contact mass as indicated by the substantial absence of oxygen from the exit gases. In order to permit this type of burn it is important to have a relatively large amount of carbon deposited on the catalyst.

This narrow flame front type of regeneration has been found to be preferable since it permits more efficient use of the oxygen content of the reactivating gas and eliminates the necessity for employing extraneous heat carrier media for removing the heat of combustion. Moreover, it has been found that variations over a wide range in the pressure prevailing during regeneration do not change the rate of regeneration appreciably.

Reactivation with a narrow flame front is disclosed in Liedholm Patent 2,225,402, but the patentee fails to disclose the specific conditions under which the cracking operation must be carried out so as to insure obtaining a carbonaceous deposit that can be regenerated in this manner. Also the patentee apparently does not contemplate a process in which the conversion period of the process extends for more than about 1 hour or a fraction thereof.

We have discovered that in order to effect regeneration of the contact mass employing the narrow flame front type of combustion it is advantageous for the amount of carbon deposited upon the catalyst to be in excess of about 3% and preferably in the range 5 to 15% by weight of the catalyst.

We have also found that by suitable correlation of conditions of operation prevailing during the conversion period the length of the conversion period can be prolonged to substantially in excess of 1 hour, obtaining a relatively high rate of conversion to gasoline while forming a carbonaceous deposit upon the contact mass to the extent above mentioned. The conditions of operation which have been found suitable are generally similar to those disclosed in our co-pending applications, Serial No. 313,654, filed January 13, 1940 (now U. S. 2,319,590) and Serial No. 409,488, filed September 4, 1941.

Thus, it is contemplated employing a cracking catalyst of high and sustained activity, such as a catalyst giving an average conversion in excess of 15% and preferably in excess of 25% by weight of gasoline plus gas over a conversion period in excess of 4 hours and of the order of about 10 to 20 hours or more, the longer the conversion period the lower the average per cent conversion. The heated feed oil in the vapor phase is subjected to contact with the catalyst at a temperature in the range 850 to 1100° F. and preferably at a temperature of about 950 to 1050° F. Pressures of the order of atmospheric up to about 200 pounds per square inch may be employed.

The charge oil is passed through the contact mass at a space velocity in the range about 1 to 10 and preferably in the range about 3 to 6 (expressed as the total liquid volume of the charge per hour at 60° F. divided by the total volume occupied by the catalyst). Moreover conditions of fluid flow through the catalyst mass are maintained such that the modified Reynolds number as determined by the following equation, has a

value of about 40 or 50 and above and preferably in the range of 100 to 1000.

$$R = \frac{D_p U P}{Z}$$

where

R is the modified Reynolds number;

D_p is the diameter of the catalyst particles in feet; U is the average velocity in feet per second of fluid mixture flowing through the catalyst zone, the zone being regarded as empty;

P is the average density in pounds per cubic foot of fluid mixture flowing through the empty zone at the temperature and pressure prevailing during the conversion period;

Z¹ is the viscosity of the fluid mixture flowing through the empty zone in pounds per foot per second under the operating conditions of temperature and pressure.

It is advantageous to select as the charge to the conversion reaction a hydrocarbon oil feed stock which is of clean character and good color characterized by having a carbon residue of less than 0.2% and a color of less than 200 as measured on the Lovibond 1/2 inch scale. Various types of feed stocks having these characteristics can be employed such as kerosene, gas oil and other heavy distillates and even topped crudes and residuals which have been treated to bring them within the characteristics mentioned above.

Furthermore, in heating the feed stock to the reaction temperature it is advantageous to raise the oil to the conversion temperature under conditions such that it undergoes no deleterious change in composition prior to contact with the catalyst. Deleterious change in composition is evidenced by excessive carbon deposition upon the catalyst during conversion of the oil.

When operating under the foregoing conditions, it has been found that the conversion period of the operating cycle can be substantially prolonged, for example, to about 3 to 4 hours and even as high as 8 to 20 hours. The conversion rate drops off only a comparatively small amount

as the conversion period is prolonged to within the range set forth above. The rate of carbon deposition on the catalyst also decreases such that the ratio of gasoline to carbon with an extended conversion period is much greater than with a relatively short period. This is indicated by the following table comparing the results obtained when cracking a virgin gas oil having an A. P. I. gravity of 30, a color on the 1/2 inch Lovibond scale of 75, a carbon residue of 0.04%, and boiling within the range of about 430° F. to 800° F.:

Conversion period, hours	Yield of gasoline,* per cent by weight of feed oil	Yield of carbon, per cent by weight of feed oil	Ratio gasoline to carbon	Yield of carbon, per cent by weight of catalyst
1.....	27.0	0.35	71	1.0
2.....	23.5	0.29	80	2.0
4.....	20.4	0.24	85	3.4
8.....	18.1	0.16	100	4.6
12.....	17.0	0.13	130	5.4

* 400° F. end point gasoline with a Reid vapor pressure of 9.5 pounds.

¹ The value Z is determined by multiplying the absolute viscosity of the reaction mixture in centipoises by the factor 0.000672. The viscosity of hydrocarbons at the temperature of conversion may be determined by reference to the nomograph on page 608, Ind. Eng. Chem., vol. 28, No. 5 (article entitled "High Temperature Viscosities of Liquid Petroleum Fractions" by Watson, Wien and Murphy).

The foregoing data are illustrative of results obtainable in cracking the gas oil in question by contact with a synthetic silica-alumina-zirconia catalyst of reduced activity by virtue of previous use, the approximate composition of the catalyst being about 75% SiO_2 , 20% Al_2O_3 , and 5% ZrO_2 by weight, and the catalyst being used in the form of cylindrical pellets $\frac{1}{8}$ inch in diameter and in length.

These results are based on operating conditions involving a reaction temperature of about 925° F., a reaction pressure of about 35 pounds gauge, a space velocity of oil vapors through the catalyst of about 3 (volume of charge as liquid at 60° F. divided by the total volume occupied by the catalyst per hour), and a modified Reynolds number of about 700 and above.

As the tabulation shows, with a conversion period of two hours, the ratio of gasoline to carbon produced is about 80, whereas with successively longer periods of conversion this ratio is increased to as much as 130 with a conversion period of twelve hours. In other words, the per cent reduction in gasoline yield by extending the conversion period from two to twelve hours is about 28%, whereas the reduction in carbon is about 55%. Furthermore, it will be observed that by operating with a conversion period of about four hours, the carbon deposited upon the catalyst amounts to about 3.4% by weight of the catalyst, and therefore in an amount sufficient to permit regeneration of the catalyst by narrow flame front burning.

With a fully active catalyst the conversion yield of gasoline would be higher than that shown in the above tabulation. Likewise the yield of carbon would be correspondingly higher. However, the rate of carbon deposition on the catalyst in a catalytic cracking operation is affected by the modified Reynolds number maintained during the conversion of the oil. Thus by operating so that a modified Reynolds number of lower value obtains, the rate of carbon deposition will be greater.

For example, when operating with a reaction temperature of about 920° F., a reaction pressure of about 40 pounds per square inch gauge, a space velocity of 3, with a modified Reynolds number of about 65, and using a fully active catalyst of the same composition as above, the following approximate yields are obtained for a three-hour conversion period:

Yield of 40° end point gasoline of 9.5 Reid vapor pressure _____ 30% by volume—basis feed oil
Yield of carbon _____ 0.63% by volume—basis feed oil
Yield of carbon _____ 7.5% by weight—basis catalyst

The foregoing results are based on operations in which cracking is effected in the vapor phase in a reaction zone packed with the catalyst in pelleted form, the catalyst mass having a free space of about 35%.

The contact mass containing the carbonaceous deposit can be activated by passing a mixture of flue gas and oxygen therethrough. The gas advantageously enters the contact mass at a temperature of about 750-950° F. The oxygen content of the entering gas mixture is maintained within the range about 1 to 5% and usually 1 to 2%. The reactivating gas is passed through the contact mass at a space velocity which may range from about 20 to 100 (space velocity defined as the number of volumes of reactivating gas meas-

ured at 32° F. and atmospheric pressure which is passed through a unit volume of catalyst bed per minute). The regeneration pressure may vary from atmospheric up to about 10 atmospheres or more absolute.

By adjusting the oxygen content and the volume of the gas the reactivation may be confined to a relatively thin section which propagates from the inlet to the outlet of the reaction zone, substantially all of the heat of reactivation being removed as sensible heat of the regeneration gases. Moreover, the entire catalyst mass can be reactivated in a period of time substantially less than the conversion period.

After switching the feed oil vapor to a catalyst chamber containing reactivated catalyst it is customary to purge the catalyst chamber from which the oil vapor stream was switched with oxygen free flue gas to remove hydrocarbons remaining in the catalyst mass. It has been found advantageous, however, to avoid excessive purging after this switching since excessive purging results in a material reduction in the temperature of the spent catalyst mass and also tends to remove hydrocarbon material, the presence of which is desirable from the standpoint of aiding ignition of the carbonaceous deposit on the catalyst in the regeneration operation.

For example, the purge gas should not exceed 10 volumes and preferably should not exceed 4 volumes of gas (measured at the temperature and pressure prevailing in the catalyst chamber during conversion) per volume of catalyst. Moreover, by restricting the volume, the purged gas and entrained hydrocarbons may be discharged directly into the fractionating system without disturbing the fractionating operation unduly.

Reference will now be made to the accompanying drawing for the purpose of illustrating briefly the method of operation.

As indicated, feed oil drawn from a source not shown is forced by a pump 1 to an oil heater 2 wherein the oil is vaporized and heated to a temperature of about 950° F. The hot oil vapors are then conducted through a pipe 3 to catalyst chambers 4 and 4'. The chambers are manifolded together as indicated to permit maintaining one chamber onstream, while the other is offstream and undergoing regeneration. Thus, chamber 4 may be regarded as onstream, in which case the heated hydrocarbon vapors pass downwardly through the catalyst mass within the chamber during which passage the hydrocarbons undergo conversion. The products of reaction are removed from the bottom of the chamber 4 and are drawn off through a pipe manifold and conducted through a pipe 5 to a fractionator 6.

In the fractionator 6 the converted hydrocarbons are subjected to fractionation to form a vapor fraction containing gasoline hydrocarbons and normally gaseous hydrocarbons and a higher boiling liquid fraction comprising gas oil which latter is drawn off through a pipe 7 for such further disposition as may be desired.

The vapor fraction is drawn off from the top of the fractionator through a pipe 8 to a condenser and cooler 9. The resultant condensate and uncondensed gases are drawn off to an accumulator 10. Gaseous constituents collecting therein are drawn off through a pipe 11, while the liquid portion collecting therein and comprising naphtha is drawn off through a pipe 12.

As indicated in the drawing a portion of the

conversion mixture passing through the pipe 5 to the fractionator 6 may be diverted through a branch pipe 13. The diverted vapor mixture is recycled by means of a blower 13' to the inlet of the chamber 4. One purpose of this recycling through the reaction chamber is to increase the volume of hydrocarbons flowing therethrough during conversion and thereby provide a means of increasing the modified Reynolds number to which reference has previously been made.

The flow of hydrocarbons through the chamber 4 is continued for a period of about 4 hours or longer until it becomes desirable to regenerate the catalyst.

When regeneration becomes necessary the flow of hydrocarbon vapor is switched from the chamber 4 to the chamber 4' containing fresh or regenerated catalyst. This is accomplished by adjusting the valves in the pipe manifolds leading into and away from the chambers 4 and 4'. The chamber 4 is then offstream during which time the catalyst contained therein undergoes regeneration.

Prior to such regeneration, however, the chamber is purged with oxygen-free flue gas or other inert gas contained in a storage tank 14. The gas in the storage tank is maintained under sufficiently high pressure to force the purged gas through the reaction chambers and to bring the offstream chamber up to whatever pressure is desired for the regeneration operation.

Thus, the purged gas is conducted through pipe 15, communicating with a pipe 16 leading to the pipe manifold at the inlet of the reaction chambers. This purged gas is forced through the offstream reaction chamber 4 to remove hydrocarbons remaining therein. The exit gas containing entrained hydrocarbons is discharged through the bottom manifold into the pipe 5 and from there is discharged into the fractionator 6. As previously stated the amount of purged gas passed through the reaction chamber is advantageously restricted to not in excess of about 4 volumes of gas per volume of catalyst mass. In this way the temperature of the catalyst mass will not drop more than about 20° F. below the conversion reaction temperature.

Thereafter the outlet valves are adjusted so as to bring the purged reaction chamber to the pressure level desired for regeneration. As soon as this is done the regenerating gas discharged by a circulating blower 17 is cut into the reaction chamber. Air or oxygen is introduced to the circulating stream in small amount by a pump or compressor 18. The amount of air introduced is advantageously sufficient to maintain an oxygen content in the recirculating gas of about 1 to 2% by volume.

The circulating blower 17 is advantageously maintained operating at a substantially constant rate so as to cause a continuous flow of reactivating gas through the offstream reaction chamber 4. The exit gas is conducted from the bottom manifold through a pipe 23 which leads to a waste heat boiler 19 and from there through a pipe 20 containing a screen 21 to the inlet of the circulating blower 17.

The waste heat boiler serves to abstract heat from the exit reactivating gas and to cool it to a temperature of about 750 to 950° prior to passage through the circulating blower.

The screen 21 serves to remove entrained dust or powder.

Excess gas is drawn off through a branched pipe 22 from which it may be discharged through

a suitably controlled valve to the atmosphere or disposed of in some other fashion.

The rate of flow, and the oxygen content, of the circulating gas is adjusted so as to maintain a narrow flame front of combustion within the reaction chamber as has been described previously. Sufficient volume of inert gas is passed through the catalyst mass undergoing regeneration to absorb exothermic heat of regeneration 10 and to remove it therefrom as sensible heat in the gas issuing from the catalyst mass. More specifically conditions are maintained such that substantially all of the exothermic heat of regeneration is removed as sensible heat in the gas, 15 while maintaining the temperature of the catalyst mass not in excess of about 1200° F.

Substantially complete regeneration of the catalyst mass is evidenced by an abrupt drop in temperature of the effluent reactivating gas and 20 by the appearance of oxygen in the effluent gas. At this point it becomes desirable to purge the regenerated mass so as to remove residual oxygen.

Purging for this purpose is accomplished by closing a valve 26 in the suction of the blower 25 25 and allowing the catalyst mass to be purged by oxygen-free gas from the pressure storage tank 14. In other words, circulation of reactivating gas through the blower 17 is substantially entirely stopped during this purging step so as 30 to avoid contamination of the purge gas with any residual oxygen or oxygen-containing gas that may remain in the system.

The effluent purge gas containing residual oxygen is discharged through the regenerating gas 35 cooler, pipe 28 and pipe 22.

As indicated in the drawing a branch pipe 24 containing a control valve 25 may be provided which communicates with the pipe 20 and the pressure storage tank 14. During regeneration 40 of the catalyst mass oxygen-free gas produced during regeneration, particularly where regeneration is being carried out under a pressure substantially above that prevailing during hydrocarbon conversion, may be conducted through the pipe 24 and valve 25 to the tank 14, thereby restoring the supply of high pressure purge gas.

A pressure of about atmospheric or substantially above may be maintained in the reaction chambers during hydrocarbon oil conversion. 50 The same or substantially higher pressures may prevail during reactivation of the catalyst masses. It is advantageous to employ pressures of 100 pounds and above during reactivation, particularly from the standpoint of reducing the volume of the recirculating gas. For example, a pressure of about 25 to 40 pounds may prevail during hydrocarbon conversion, while a pressure of 100 to 150 pounds or higher may prevail during reactivation.

While a synthetic alumina-silica-zirconia type catalyst has been specifically mentioned, it is contemplated that other catalysts may be employed.

Various acid-treated and metal-substituted 65 clays, such as the Super-Filtrols, are satisfactory. Likewise, the acid-treated and metal-substituted natural or artificial zeolites, such as the artificial zeolite known as Doucile, can be used. Various metals can be substituted in the clays or zeolites, such as uranium, molybdenum, manganese, lead, zinc, zirconium, nickel and the like. Likewise the combination of certain acid-treated active clays of the character of Filtral, together with added proportions of alumina or silica or both can be employed. Alumina alone may be used under

certain conditions. The synthetic silica-alumina catalysts can be improved by the addition of other constituents, such as zirconium oxide or molybdenum oxide. Other catalysts which are not silica-alumina catalysts, either synthetic or prepared from natural minerals, have been found which satisfy the characteristics of the catalyst of the present invention. Examples of other suitable catalysts comprise metallic halide compounds such as the halides of aluminum and chromium, etc. In general, a catalyst is employed which is stable at high temperatures of the order of 1400 to 1600° F., as determined by calcining in a muffle furnace at that temperature, and which is a measure or indication of the ability of the catalyst to maintain its activity under the customary temperatures of reactivation of the order of 1100 to 1400° F., as measured by thermocouples within the catalyst bed during the reactivation cycle. It is preferred to employ a catalyst which is substantially free from alkali and alkaline earth metals.

Also if desired the conversion reaction may be carried out in the presence of light gases such as hydrogen and hydrogen-containing gases, including gases produced in the reaction and which may be recirculated through the heating and conversion zones or through the conversion zone only.

In the appended claims the term "fragmentary" used with reference to the catalyst is employed in a generic sense to include all forms in which a solid catalyst may be used, for example, powder, particles, granules, lumps, pellets and pills, etc.

Obviously many modifications and variations of the invention as above set forth may be made without departing from the spirit and scope thereof, and therefore only such limitations should be imposed as are indicated by the appended claims.

We claim:

1. In the catalytic cracking of hydrocarbon oil to convert the same to gasoline hydrocarbons during passage through a bed of active cracking catalyst within a reaction zone involving alternate periods of oil conversion and catalyst regeneration in situ, carbon being deposited upon the catalyst during the conversion periods and being removed therefrom by combustion during the regeneration periods by flow of combustion gases containing about 1 to 2% oxygen at a gas space velocity of about 20 to 100 through the bed from inlet to outlet of the reaction zone, substantially all of the heat of combustion being removed entirely as sensible heat of the effluent gas without exposing the catalyst mass to temperatures above about 1250° F., the method which comprises heating a feed oil consisting essentially of normally liquid hydrocarbons having a carbon residue of less than 0.2% and a color of less than 200 on the Lovibond $\frac{1}{2}$ " scale to a temperature in the range 850 to 1100° F., passing the heated oil in vapor phase through the catalyst mass at a space velocity in the range 1 to 10, maintaining a rate of hydrocarbon flow through the mass corresponding to a modified Reynolds flow number in the range 100 to 1000, continuing the flow of hydrocarbons through the mass without interruption for regeneration for a period substantially in excess of 1 hour until carbonaceous deposit formed on the catalyst amounts to about 5 to 15% by weight of the catalyst, at least about 17% by weight of the feed oil being converted into gasoline thereafter interrupting the flow of hy-

drocarbons through the catalytic mass, and regenerating said mass in situ while confining reactivation to a relatively thin section which propagates from inlet to outlet of said reaction zone.

2. The method according to claim 1 in which the hydrocarbon flow is continued through the catalyst mass during the onstream period for at least 3 hours.

3. In the catalytic cracking of hydrocarbon oil to convert the same to gasoline hydrocarbons during passage through a bed of active cracking catalyst within a reaction zone involving alternate periods of oil conversion and catalyst regeneration in situ, carbon being deposited upon the catalyst during the conversion periods and being removed therefrom by combustion during the regeneration periods by flow of combustion gases containing about 1 to 2% oxygen at a gas space velocity of about 20 to 100 through the bed from inlet to outlet of the reaction zone, substantially all of the heat of combustion being removed entirely as sensible heat of the effluent gas without exposing the catalyst mass to temperatures above about 1250° F., the method which comprises heating a feed oil consisting essentially of normally liquid hydrocarbons having a carbon residue of less than 0.2% and a color of less than 200 on the Lovibond $\frac{1}{2}$ " scale to a temperature in the range 950 to 1050° F., passing the heated oil in vapor phase through the catalyst mass at a space velocity in the range 3 to 6, maintaining a rate of hydrocarbon flow through the mass corresponding to a modified Reynolds flow number in the range 100 to 1000, continuing the flow of hydrocarbons through the mass without interruption for regeneration for a period of at least 3 to 4 hours until carbonaceous deposit formed on the catalyst amounts to about 5 to 15% by weight of the catalyst, at least about 17% by weight of the feed oil being converted into gasoline, thereafter interrupting the flow of hydrocarbons through the catalytic mass, and regenerating said mass in situ while confining reactivation to a relatively thin section which propagates from inlet to outlet of said reaction zone.

4. In the catalytic cracking of hydrocarbon oil to convert the same to gasoline hydrocarbons during passage through a bed of active cracking catalyst within a reaction zone involving alternate periods of oil conversion and catalyst regeneration in situ, carbon being deposited upon the catalyst during the conversion periods and being removed therefrom by combustion during the regeneration periods by flow of combustion gases containing about 1 to 2% oxygen at a gas space velocity of about 20 to 100 through the bed from inlet to outlet of the reaction zone, substantially all of the heat of combustion being removed entirely as sensible heat of the effluent gas without exposing the catalyst mass to temperatures above about 1250° F., the method which comprises heating a feed oil consisting essentially of normally liquid hydrocarbons having a carbon residue of less than 0.2% and a color of less than 200 on the Lovibond $\frac{1}{2}$ " scale to a temperature in the range 950 to 1050° F., passing the heated oil in vapor phase through the catalyst mass at a space velocity in the range 3 to 6, maintaining a rate of hydrocarbon flow through the mass corresponding to a modified Reynolds flow number in the range 100 to 1000, continuing the flow of hydrocarbons through the catalytic mass without interruption for regeneration for a period substantially in excess of 1 hour until carbonaceous deposit formed upon the catalyst

amounts to about 5 to 15% by weight of the catalyst, a substantial portion of the feed oil being converted into gasoline and the ratio of gasoline to carbon being produced when the catalyst has been onstream for substantially more than 1 hour being substantially greater than that obtained during a period of 1 hour and less, there-

5 after interrupting the flow of hydrocarbons through the catalyst mass, and regenerating said mass in situ while confining reactivation to a relatively thin section which propagates from inlet to outlet of said reaction zone.

DU BOIS EASTMAN.
